UNITED STATES PATENT OFFICE

ROBERT G. PILKINGTON, OF UTICA, NEW YORK, ASSIGNOR TO DIVINE BROTHERS COMPANY, OF UTICA, NEW YORK, A CORPORATION

POLISHING-WHEEL-HEADING MACHINE

Application filed March 19, 1928. Serial No. 262,766.

My present invention relates to a polishing-wheel heading machine, meaning thereby a machine for performing part or all of the steps necessary to secure an abrasive to a polishing-wheel by an adhesive.

Heretofore the common and accepted method of placing the "head" that is the abrasive with the necessary adhesive upon the polishing-wheel has been to apply the glue or other adhesive to the periphery of the polishing-wheel by a workman brushing the glue on to the wheel and the rolling the glue-covered periphery of the polishing-wheel in a supply of abrasive, the abrasive being forced into the glue by the operator pressing the wheel as he rolls it. This manual forming of the head upon a polishing-wheel consumes a large amount of time and results in a large proportion of poor or irregular "heads" on account of the varying care, strength and skill of the operator.

The purpose of this invention is to overcome the disadvantages of hand-made heads upon polishing-wheel and to provide a machine for performing the various steps necessary and to perform these steps quicker, better, more economically and with greater regularity and uniformity.

A further purpose is to provide a machine of the class described wherein means are provided for receiving and rotating a polishing-wheel of any varying size within the range of the machine and for quickly placing upon the periphery of the polishing-wheel a sufficient and uniform layer of glue or other adhesive; and then without removing the polishing-wheel from the machine; but simply by changing its position in the machine, placing a sufficient and uniform layer of the abrasive upon the adhesive covered surface of the polishing-wheel and continuing the supply of said abrasive until a sufficient amount has been placed upon the wheel and then rolling or packing the abrasive into the adhesive with greater pressure if necessary than used in the abrasive supplying step; such packing pressure being readily maintained at an even amount for the whole wheel and continued at the same pressure for wheels of the same type; but adapted to be set to give another pressure

as may be needed on other types of wheels.

Another purpose of my invention is to provide a machine of the character described wherein a glue-supplying wheel and an abrasive supplying and packing-wheel are revolvably mounted in spaced relation with a movable member or members such as rocker arms between said wheels with said rocker arms adapted to removably receive an arbor, carrying the polishing-wheel to be given a head and to have said arms adapted to be swung first towards the gluing-wheel for the polishing-wheel to receive the glue therefrom and then while the glue is still hot upon the polishing-wheel to have the arms swing away from the gluing-wheel and carry the polishing-wheel into engagement with the abrasive supplying-wheel, which wheel also acts as the packing-wheel to pack or press the abrasive into the glue on the polishing-wheel, and after the packing operation has been completed to have the arms adapted to swing to an intermediate position where the arbor can be removed; the completed polishing-wheel removed therefrom and another polishing-wheel placed upon the arbor and then the arbor placed in the machine, whereupon the complete operation is again repeated.

Further purposes of the invention are to provide improved combinations of the parts and additional parts combining with the machine to perfect its operation, such as a movable mounting for the glue-pot whereby the amount of glue placed upon the gluing-wheel can be controlled or the glue-pot removed entirely from the glue-wheel as for intervals when the machine is not in operation, means for operating and equalizing the amount of glue upon the gluing-wheel, means for regularly and evenly supplying abrasive to the abrasive-supplying wheel and means to recover the abrasive not placed upon the head of the polishing-wheel and to separate the clean abrasive from the abrasive having any glue in contact therewith.

Fig. 1 is a side elevation of a machine embodying this invention.

Fig. 2 is a top or plan view of the machine; but with the abrasive receptacle and its support removed.

Fig. 3 is a transverse vertical sectional view through the machine on line 3—3 of Fig. 1.

Fig. 4 is a plan view of the abrasive distributor.

5 Fig. 5 is a central longitudinal sectional view of said distributor together with a part of the rear vibrator wheel.

Fig. 6 is a transverse sectional view of said distributor on line 6—6 of Fig. 4.

10 Fig. 7 is a horizontal sectional view on a line of the counter shaft 65.

Fig. 8 is a detail elevation of the glue distributing means as seen from the left thereof on Fig. 1 and Fig. 9 is a vertical sectional view on line 9—9 of Fig. 8.

15 Fig. 10 is a detail sectional view on line 10—10 of Fig. 2 of the weighted lever 96, bracket casing 92 and pawl 124 in operative connection therewith.

20 Referring to the drawings in a more particular description, it will be seen that the machine comprises a bed-plate 20 supported by suitable legs 21, a platform 22 over a part of the bed-plate and supported thereabove by 25 upright posts 23 and 24 upstanding from the bed-plate 20, two spaced side frame members 25 carrying two spaced rocking arms 26, a gluing wheel 27 and an abrasive supplying and packing wheel 28 revolvably mounted 30 upon the framework of the machine on the opposite sides of said rocker arms and with said rocker arms provided at their upper end with open topped bearings to removably receive an arbor 29 which removably carries 35 the polishing-wheel 30, that is to receive its head of adhesive and abrasive.

Conveniently placed upon the framework of the machine as upon the bed-plate 20, there is provided a main motor 31 adapted through 40 speed reducing device 32 to drive transversely extending shaft 33 at proper speed to rotate the glue wheel 27 and packing wheel 28 by means of chain 34 engaging toothed wheels 35 and 36 respectively mounted upon the 45 shafts carrying the gluing-wheel 27 and the packing-wheel 28.

As the machine is illustrated in Figs. 1 and 2 of the drawings, the gluing-wheel 27 is towards the right hand end of the machine and 50 is revolvably carried by being fixed upon a horizontally arranged transversely extending shaft 37 mounted in bearings 38, provided upon the upper ends of the front and rear posts 39 and 40 upstanding from the bed-plate 20 of the machine. Said shaft projects 55 beyond the rear bearing 38 and is there provided with the toothed-wheel 35 already mentioned as being driven by main drive-chain 34.

55 Surrounding the lower portion of the gluing wheel 27 there is provided the glue-pot 41 adapted to hold a sufficient supply of liquid glue or other adhesive 42; which glue is kept sufficiently soft and warmed for proper application by the presence of hot water 43

in the water tank 44 placed below the glue pot 41 with the sides of the tank coming up about the sides of the glue-pot but spaced therefrom and with the tank preferably closed and rendered practically steam tight by the laterally 70 extending flange 45 on the glue-pot resting upon the upper edge of the side walls of the tank 44. The glue-pot flange 45 also serves the purpose of removably supporting the glue-pot in the tank.

75 The glue-pot and its heating tank 44 is mounted to be bodily moved vertically towards and from the gluing-wheel 27 in order to vary the amount of glue placed upon the gluing-wheel by varying the extent to which the gluing-wheel is immersed in the glue. When the machine is not to be used for some time or when the glue-pot is to be cleaned out, the glue-pot and tank are lowered below the level of the glue-wheel so that the wheel 80 will not stand in the glue and so that the glue-pot may be removed if desired.

85 The glue-pot and its heating tank are mounted for such vertical movements by the tank 44 being placed on top of the movable 90 table 46, which is mounted for vertical movement by having relatively long vertical slide-ways 47 at its opposite sides engaging and sliding upon the front and rear posts 39 and 40, which form the frame for carrying the 95 gluing-wheel shaft. Vertical movement is imparted to this table by means of a threaded rod 48 fixed to and depending from the table 46, being engaged by a nut 49 surrounding the rod and suitably supported upon the bed-plate 20 of the machine with said nut being 100 formed integral with or securely fastened to a bevel gear 50 which in turn is engaged by a bevel gear 51 mounted on a horizontal shaft 52 carried in suitable bearings 53 and 54 with 105 said shaft 52 rotated by a crank arm 55, having handle 56.

To the lower part of the tank 44 there is secured a short outwardly extending pipe 57 having at its outer end a T 58, to the lower end of which is attached a valve 59 whereby the water may be withdrawn from the tank. Above the T 58 projects a pipe 60 with a funnel 61 at its upper end for supplying 110 water to the tank.

115 The two rocker arms 26 are mounted for rocking movement towards the right or towards the left as the machine is seen in Fig. 1 by said rocker arms being secured to a transversely extending shaft 62 mounted in suitable 120 bearings on the front and rear side frames 25. Below the lower ends of the rocker arms there is mounted in a depending position a segmental gear 63 engaged therebelow by pinion 64 on counter shaft 65 which is mounted in bearings provided in said side frames 25. The front end of this counter shaft has secured thereto a crank arm 66 with a forwardly extending handle 66^a whereby in an obvious manner manual rota- 125

tion of the arm 66 will impart a partial rotation in the opposite direction to the upstanding rocker arms 26.

The upper ends of the rocker arms 26 are each provided with an opened top or roughly V shaped recess 67. At the bottom of said recess is mounted an anti-friction roller 68 and at the opposite sides of said recess there are mounted similar anti-friction rollers 69 and 70 respectively. An arbor or shaft 29 of the proper size may now be readily placed into the bearings thus provided at the top of said rocker arms with such arbor or shaft having mounted usually removably thereon the polishing-wheel 30, that is to be given a head by the machine.

After the heading operation is completed or either step thereof is completed, the arbor and its polishing-wheel may be as readily removed from the open topped bearings of the rocker arms. In order to impart one or more layers of glue to the periphery of the polishing-wheel 30 the rocker arms are moved to the right until the periphery of the polishing-wheel is brought into sufficiently close contact with the revolving glue-wheel 27. This is done in practice by the operator pressing downwardly on the handle 66 and holding said handle down with sufficient pressure to assure the glue from the glue-wheel being transferred to the surface of the polishing-wheel.

The abrasive supplying and packing-wheel 28 is mounted the proper distance to the left from the rocker arms 26 by means of a shaft 71 mounted in suitable bearings in the two side frame members 25. To the rear of the rear frame member 25 said shaft carries its toothed wheel 36 to receive motion from the main drive chain 34. Upon the shaft 71 to the rear of the rear frame member 25 is placed a large vibrator-wheel 72 having notches 73 closely spaced along its periphery. To the front of the front frame member 25 there is placed on this shaft 71 a similar vibrator wheel 72. Both side vibrator-wheels are secured to said shaft 71 and operate to give an up and down vibrating motion to the vibrator rod 74. This rod 74 is secured to the bottom of the inclined abrasive distributor 75 towards its lower or right hand end. Towards its upper end the said distributor 75 is pivotally mounted on a rod 76 carried by two brackets 77 which in turn are mounted on the portion of the posts 23, projecting above the platform 22 at the left end of the machine. The detail construction of this abrasive distributor is shown in Figs. 4, 5 and 6, which are respectively plan, longitudinal, sectional and transverse sectional views of said distributor. It will be seen that the distributor is of shovel-like shape having a bottom 78 and an upstanding flange 79 about its forward and rear sides and its upper end. Abrasive

through a valve 82 down upon the upper end of the distributor 75. At the zone where the abrasive falls upon the distributor there is placed a diamond-shaped upstanding pyramid 83, which in obvious manner tends to at once distribute the abrasive over a considerable portion of the distributor. Farther to the right and farther down upon the main surface or bottom 78 of the distributor are placed a triangular-shaped series of smaller diamond-shaped upstanding pyramids 84. The apex of the triangular area of these smaller pyramids is in the center of the distributor and close to the zone where the abrasive falls upon the distributor. Thereafter the pyramids are arranged in staggered formation gradually increasing in number as they extend downwardly upon the distributor until they cover the full width of the distributor on a line towards the lower end of the distributor. Farther down upon the distributor are two spaced upstanding ridges 85 and 86, which tend to still further distribute evenly over the whole lower edge of the distributor the abrasive which has been separated into a number of little streams of abrasive by the guiding action of the pyramids and by the vibrating action imparted to the distributor by the up and down motion given by the vibrator-wheels.

The abrasive receptacle 81 is supported in a bracket 87 carried by one of the upstanding posts 23. Below the bracket arms 77 there project from the front and rear posts 23 suitable brackets 88 extending to the right and carrying a shaft 89 which carries an idler toothed-wheel 90, receiving a loop of the main drive chain 34 to the left of wheel 36 so that clockwise motion may be imparted to the packing-wheel 28.

Assuming that a polishing-wheel has been placed in the rocker arms as already described and has received its supply of glue by being brought into contact with the glue-wheel, the operator will then move the crank arm 66 in a clockwise direction, moving the polishing-wheel 30 to the left and into engagement with the wheel 28. It will be understood that when the machine is in operation a widely distributed supply of the abrasive will be continuously dropping from the lower edge of the distributor 75 on to the upper right hand quarter of the packing-wheel 28, which part of the wheel is moving downwardly and is constantly being brought into contact with the glue covered surface of the polishing-wheel. Manual pressure of the operator upon the handle 66 is sufficient to hold the polishing-wheel in contact with the wheel 28, while said polishing-wheel is receiving its layers of abrasive. The weight of the arms 26 and of the polishing-wheel 30 will also tend to hold the polishing-wheel in contact with the wheel 28.

After one or two or perhaps three rotations

of the polishing-wheel 30 upon the wheel 28 the glue on the polishing-wheel becomes fairly well covered with the abrasive and it is desirable to apply greater pressure to the 5 abrasive in order to "pack" the abrasive down into the layer of glue. By placing greater pressure upon the abrasive and glue upon the polishing-wheel the abrasive is packed down into the glue instead of simply 10 remaining on the surface of the glue allowing more abrasive to be placed upon the polishing-wheel and causing the abrasive to be more nearly uniform throughout the thickness of the "head" of the polishing-wheel. As this packing process continues 15 and the abrasive is pushed down into the glue more abrasive can be added to the surface of the head and some of this subsequently added abrasive can on subsequent rotation of the 20 polishing-wheel be crowded into the thickness of the head instead of remaining upon its surface. This packing process can be continued until a sufficient amount of abrasive has been incorporated into the head.

25 It will be understood on the first one or two rotations of the glue covered polishing-wheel against the glue supplying wheel 28 only enough pressure will be placed upon the polishing-wheel to transfer the abrasive from 30 the surface of the wheel 28 to the glue covered surface of the polishing-wheel. Too much pressure at this stage of the proceeding would disturb the glue upon the polishing-wheel or cause the glue to roll up on the polishing-wheel ahead of its line of contact with the 35 wheel 28. After a fair coating of abrasive has been placed upon the glue of the polishing-wheel more pressure can properly be used without distorting the head. This first 40 additional pressure can be given by manual pressure upon the handle 66^a upon crank arm 66. In order to complete the packing operation however still greater pressure is needed and can be given by the hand upon the 45 handle 66^a. The means for applying such greater pressure upon the head by pressing the polishing-wheel 30 against the wheel 28 acting as a packing-wheel will now be described.

50 As already described and as appears in Figs. 1 and 2 of the drawings the swinging movement of the polishing-wheel 30 is effected and the initial pressure of said polishing-wheel upon the wheel 28 is brought about 55 by rotation of the shaft 65 by manual swinging of the crank arm 66 by means of the handle 66^a, with said shaft 65 having its pinion 64 in engagement with the segmental gear depending from the shaft 62, which 60 carries the rocker arms 26. As more particularly appears in Fig. 7, which is a horizontal sectional view on the line of the counter shaft 65, there is fixed upon the said shaft near its forward end a ratchet 91. Rotatingly mounted upon the shaft 65 is a bracket-

like casing 92, preferably as shown in said Fig. 7 enclosing the ratchet 91 on both sides thereof and provided with a pocket 93 in which is slidably mounted a pawl 94 for radial movement into or out of engagement 70 with the teeth upon the ratchet 91. Between the pawl and the end of the pocket away from the shaft is interposed a spring 95 operating to normally push the said pawl into engagement with the ratchet. Rigidly secured to the bracket casing 92 is a long radially extending lever 96 upon which is slidably mounted a weight 97 whereby a variable pressure may be transmitted to the shaft 65 when this weighted lever with the bracket casing 80 is connected to the shaft. Spaced along the lever 96 there is provided a plurality of holes 98 adapted to be engaged by a spring-pressed pin 99 mounted in the weight 97. When it is desired to vary the pressure, the weight 97 is adjusted along the lever by retracting the pin 99 from one hole by the means of the knob 100 on the forward end of the pin and holding the pin retracted until the weight has been adjusted to desired position and 90 opposite another hole.

In order to hold the weighted lever 96 and the bracket 92 out of rotative engagement with the shaft 65 during the gluing operation and the first part of the abrasive supplying operation, the pawl 94 is held outward from the ratchet 91. This is done by a finger 101 on said pawl extending out through a slot in the forward side of the bracket casing 92 and with the forward end of said finger pivotally connected to a link 102, the farther end of which link is pivotally connected as by headed screw 103 to the lever 104 eccentrically of the axis of said lever's pivotal mounting upon the lever 96 100 and bracket 92 by stub-shaft 105. As the parts are seen in Fig. 7 the lever 104 has been moved to the right to withdraw the pawl 94 from engagement with the pinion 91. This is the position of the parts when the shaft 65 and the rocking arms 26 are being moved simply by the hand strength of the operator. As soon as the operator desires to put additional pressure upon the polishing-wheel, the lever 104 is swung off-center and towards the shaft 65, which motion aided by the spring 95 moves the pawl 94 into engagement with the ratchet 91. At once the weight of the weighted lever 96 tends to rotate the counter-shaft 65 clockwise 110 and this motion is transmitted to the rocker shaft 62 thereabove to move the rocker arms 26 with the polishing-wheel 30 carried thereon with greater pressure towards the packing-wheel 28. If during any packing process it is desired to increase the pressure, the weight 97 is moved farther out upon the arm 96. After the packing process has been completed, the locking lever 104 is swung 115 back to the position shown in Fig. 7, there-

by disengaging the pawl 94 from the pinion and so freeing the shaft 65 from its engagement with the weighted lever. The operator then by proper motion of handle 66^a on crank arm 66 swings the rocker arms 26 to intermediate position as shown in Fig. 1 whereupon the arbor 29 is lifted from the bearings of the rocker arms and the polishing-wheel removed from the arbor and set aside to dry.

Any loose abrasive upon the wheel 28 not transferred to the polishing-wheel 30 falls from said packing-wheel 28 as it passes downwardly, into the slanting chute 105. This loose abrasive may consist of abrasive supplied to the wheel 28 when there is no polishing-wheel in engagement with the wheel 28 or it may be the abrasive towards the outer edges of the face of said wheel 28, which will not be reached by a polishing-wheel of less width than the width of the packing-wheel 28. Some loose abrasive will at times pass the polishing-wheel without being transferred to the glue-covered face of the polishing-wheel especially after the polishing-wheel has received nearly its first supply of abrasive. Any glue or adhesive sticking to the descending face of the packing-wheel 28 after it passes the polishing-wheel, will be removed therefrom by a spring-pressed blade 106 having its edge pressed against the lower side of the packing-wheel 28. Said blade is mounted by bolts 107 upon the main side frame members 25. The glue and abrasive scraped off by this blade falls into the chute 105. The abrasive and glue from chute 105 may be received into a proper receptacle and sorted or screened away from the machine, or as shown in Figs. 1 and 2 the chute may deliver this material directly into a barrel-like screen 108 rotatably mounted upon the frame-work of the machine and driven by motor 109. The clean and usable abrasive falls through the sides of this screen and may be returned from time to time to the pail holding the abrasive at the top of the machine. The lumps of glue and abrasive not passing through the screen will be removed separately and may be later treated to recover the abrasive.

To a certain extent the amount of glue placed upon the gluing-wheel and to be transferred to the packing-wheel is determined by the extent to which the gluing-wheel 27 is submerged in the glue-pot 41. Preferably however, I provide further means for regulating the amount of glue remaining upon the glue wheel when it comes into position to engage the polishing-wheel and also means for accurately and evenly distributing the glue over the whole width of the gluing wheel.

The castings at the top of the front and rear posts 39 and 40 which carry the shaft 37

of the gluing wheel 27 are extended upwardly above the level of the top of the gluing wheel. In the upper end of these extensions 110 are revolvably mounted the ends of a rod 111 which extends over the top of the gluing wheel and has fixed thereto a bracket 112 which extends to the right of the machine as shown in Figs. 1, 2 and 8. To the outer end of this bracket there is removably secured a brush 113, the bristles 114 of which project down towards the periphery of the gluing wheel. Screw-threaded means are provided for adjusting very accurately the distance or space between the bottom of the brush and the periphery of the gluing wheel. Fixed to the extreme forward end of the brush-carrying rod 111 there is a handle 115 extending to the left and a weight 116 extending to the right. The weight in an obvious manner tends to force the brush towards the gluing wheel, but downward pressure upon the handle 115 may temporarily raise the brush some distance from the wheel.

Back of the handle 115 and weight 116 but still in front of the front extension 110 there is fixedly secured to the rod 111 a bracket 117 projecting to the left of the said rod. Overhanging this bracket 117 is located the vertically screw-threaded and split end 118 of an arm 119, formed integral with or rigidly attached to the frame extension 110.

In the vertically screw-threaded aperture in the end 118 is placed the shank of the adjusting screw 120, having a large head for manual operation thereof. The lower end of the screw projects downwardly against the upper and outer end of the bracket 117. It will now be seen that lowering the screw 120 will raise the brush from the gluing wheel. When the correct or desired adjustment is obtained, accidental loosening of the screw 120 is prevented by tightening up the clamping screw 121 extending through the two parts of the split end 118 of the arm 119. It will be noted that the screw-threaded adjustment here described for locating the brush will not be interfered with by the temporary lifting of the brush by the handle 115. The brush 113 will be of a length greater than the width of the gluing wheel and will operate to distribute the glue evenly and to hold back any lumps of glue or any excess of glue.

Upon the forward post 39 for the glue-wheel support there is secured a bracket 122 having a forwardly extending arm 123 to the end of which is pivoted a pawl 124 normally hanging clear of the bracket casing 92 to which the weighted lever 96 is attached. When the operator has finished a packing operation and no longer wishes to have the weighted lever operatively connected to the shaft 65 through ratchet 91 he raises the weighted lever 96 and draws the pawl 124 on arm 123 forward to engage beneath a ledge on the bracket casing 92 and thereby sup-

ports said weighted lever and its attached parts and then he withdraws the pawl 94 from the ratchet 91 by lever 104 as already described.

6. This pawl 124 supports the weighted lever 96 until the bracket casing is to be again operatively connected to the ratchet 91 when a slight raising of the weighted lever allows the pawl 124 to swing to inoperative position.

10. What I claim as new and desire to secure by Letters Patent is:

1. In a polishing-wheel heading machine, the combination of a revolubly mounted gluing wheel, means to supply the periphery thereof with glue, a packing wheel revolubly mounted opposite to said gluing wheel, means to supply abrasive to said packing wheel, a frame between said wheels and movable in opposite directions theretowards, means for revolubly and removably mounting a polishing wheel on said frame and means for moving said frame whereby the polishing wheel may occupy an intermediate position out of contact with said glue wheel or said packing wheel or may be moved into engagement with either of said wheels.

2. In a polishing-wheel heading machine, the combination of a revolubly mounted gluing wheel, means to supply the periphery thereof with glue, a packing wheel revolubly mounted opposite to said gluing wheel and on an axis parallel to the axis of said gluing wheel, means to supply abrasive to said packing wheel, a frame between said wheels and movable in opposite directions theretowards, means for revolubly and removably mounting a polishing wheel on said frame and means for moving said frame whereby the polishing-wheel may occupy an intermediate position out of contact with said glue wheel or said packing wheel or may be moved into engagement with either of said wheels.

3. In a polishing-wheel heading machine, the combination of a revolubly mounted gluing wheel, means to supply the periphery thereof with glue, a packing wheel revolubly mounted opposite to said gluing wheel, means to supply abrasive to said packing wheel, a frame between said wheels and movable in opposite directions theretowards, means for revolubly and removably mounting a polishing wheel on said frame, means for moving said frame whereby the polishing wheel may occupy an intermediate position out of contact with said glue wheel or said packing wheel or may be moved into engagement with either of said wheels and means for increasing the pressure of the polishing wheel upon the packing wheel.

60. 4. In a polishing-wheel heading machine, the combination of a revolubly mounted gluing wheel, means to supply the periphery thereof with glue, a packing wheel revolubly mounted opposite to said gluing wheel, means to supply abrasive to said packing wheel, a

frame between said wheels and movable in opposite directions theretowards, means for revolubly and removably mounting a polishing wheel on said frame, means for moving said frame whereby the polishing wheel may occupy an intermediate position out of contact with said glue wheel or said packing wheel or may be moved into engagement with either of said wheels and additional means operatively connectible to said frame for swinging said frame and therewith the polishing wheel with increased pressure towards the packing wheel.

5. In a polishing-wheel heading machine, the combination of a revolubly mounted gluing wheel, means to supply the periphery thereof with glue, a packing wheel revolubly mounted opposite to said gluing wheel, means to supply abrasive to said packing wheel, a frame between said wheels and movable in opposite directions theretowards, means for revolubly and removably mounting a polishing wheel on said frame, means for moving said frame whereby the polishing wheel may occupy an intermediate position out of contact with said glue wheel or said packing wheel or may be moved into engagement with either of said wheels and means for increasing in a varying amount the pressure of the polishing wheel upon the packing wheel.

6. In a polishing-wheel heading machine, the combination of a packing wheel revolubly mounted, means to supply abrasive to said packing wheel, a frame opposite said packing wheel and movable towards and from said wheel, means for revolubly and removably mounting a polishing wheel on said frame, means for moving said frame whereby the polishing wheel may occupy a position out of contact with said packing wheel or may be moved into engagement with said packing wheel, and means for increasing the pressure of the polishing wheel upon the packing wheel.

7. In a polishing-wheel heading machine, the combination of a packing wheel revolubly mounted, means to supply abrasive to said packing wheel, a frame opposite said packing wheel and movable towards and from said wheel, means for revolubly and removably mounting a polishing wheel on said frame, means for moving said frame whereby the polishing wheel may occupy a position out of contact with said packing wheel or may be moved into engagement with said packing wheel, and further means operatively connectible to said frame for increasing the pressure of the polishing wheel upon the packing wheel.

8. In a polishing-wheel heading machine, the combination of a packing wheel revolubly mounted, means to supply abrasive to said packing wheel, a frame opposite said packing wheel and movable towards and from said wheel, means for revolubly and removably

mounting a polishing wheel on said frame,
means for moving said frame whereby the
polishing wheel may occupy a position out of
contact with said packing wheel or may be
5 moved into engagement with said packing
wheel, and means for increasing in a varying
amount the pressure of the polishing wheel
upon the packing wheel.

In witness whereof I have affixed my signature,
10 this 17th day of February, 1928.

ROBERT G. PILKINGTON.
